JAMES G. GIRLING, OF HARTFORD, CONNECTICUT, ASSIGNOR TO THE ARROW ELECTRIC COMPANY, OF HARTFORD, CONNECTICUT, A CORPORATION OF CONNECTICUT.

PULL-SOCKET.

1,158,200.

Specification of Letters Patent.

Patented Oct. 26, 1915.

Application filed May 19, 1915. Serial No. 29,178.

To all whom it may concern:

Be it known that I, JAMES G. GIRLING, a citizen of the United States of America, and residing in the city of Hartford, county 5 of Hartford, and State of Connecticut, have invented a certain new and useful Improvement in Pull-Sockets, of which the following is a specification.

My invention relates to pull sockets and 10 more particularly to porcelain pull sockets, the object of my invention being to provide an improved pull connection for the switch mechanism in sockets of this nature.

In the accompanying drawing, Figure 1 15 is a side elevation of a porcelain pull socket in which my invention is embodied; and Fig. 2 is a vertical section therethrough.

The present invention relates to electric lamp sockets in which the switch mechanism 20 is mounted within a porcelain casing, and specifically to sockets of this character in which the switch mechanism is of the pull type.

The object of my invention is to provide 25 an easy running, insulated pull element for actuating the switch mechanism.

As here shown, the present socket comprises a casing body 10 of porcelain or the like, carrying a cap 11 which incloses the 30 wire terminals mounted on the upper button 12 of the socket body located in the switch chamber 13 of the casing and supported on the diaphragm 14 of the latter. The switch mechanism is of well known ratchet type 35 having a pivoted actuating plate 15 carrying a chain rail 16 and subjected to the influence of the return spring 17. Secured to the chain rail is a pull chain 18 provided at its securing end with a smooth, flexible, 40 insulating cord 19, the chain end of which is gripped by a ferrule 20 which also grips the end ball of the chain. This cord 19 passes from the chain rail 16 to the exterior of the socket through a hole 21 in the latter 45 and is of sufficient length to extend well outside the socket in all positions of the switch mechanism. Consequently the chain 18 does not enter the casing, does not have to pass over the relatively thin edge of the porcelain 50 wall at the hole 21, and is in no danger of coming into contact with electrically alive portions of the socket within the switch chamber 13.

As heretofore constructed, porcelain 55 sockets of the pull type have been operated

by pull chains which extend into the socket to the switch actuating mechanism. The wall of the porcelain casing is necessarily so thin however, (in order to reduce weight, cost and improve appearances) that a chain 60 does not pass freely over the edge of the hole but rasps thereover as each successive ball passes through the opening. This results not only in a noisy operation of the switch, but also in an abrasion of the glaze 65 at the hole and the operation of the switch becomes more and more defective in accordance with the extent of its use. As a consequence it has become common to form a bell 70 at the hole 21 in order to support the chain and let it run freely and smoothly. A projecting bell of this character however is readily broken and when broken, its sharp edges not only wear the chain but catch it and prevent the free actuation of the pull 75 chain. Moreover a metallic guide bell is not harmonious with the porcelain casing and detracts from the appearance of the fitting.

The present invention obviates the necessity for the bell, since the flexible cord 80 passes as freely over the edge of the hole 21 in the porcelain as it does over a bell. Being smooth and passing easily over the surface enamel of the porcelain, it does not chip or wear the latter and the hole consequently 85 remains smooth indefinitely. Being an insulator, it affords an effective insulation for the outer pull end of the chain. It further insures a relatively silent operation 90 of the switch mechanism.

I am aware that a flexible cord has previously been suggested as a pull element for switches. So far as I am aware however it has been used only in connection with chain bells and where chains would operate equally 95 well and it has been used solely for its lightness. So far as I know, it has never been combined with a chain as a pull element nor has it been combined with a chain at the end of the latter which is secured to the 100 switch mechanism, nor has it been employed with a porcelain socket where its value is essentially due to its mechanical flexibility and its character as an insulator. It may be pointed out that the addition of the chain 105 to the pull end of the cord had the advantage of maintaining the latter taut and straight; an important feature since cord used alone is light and apt to warp with moisture.

The precise nature of the cord may be 110

varied. That here shown is round and woven in tubular form so that it presents a rounded, smooth surface to the edge of the porcelain. The switch construction may be 5 of any type having a pull operated actuating mechanism.

I claim as my invention:—

An electric lamp socket comprising a porcelain casing having a guide hole in its side 10 wall, a switch mechanism of the pull-actuated type within the casing and a pull element therefor having at one end a flexible, smooth cord of insulating material passing 15 in through said hole in the casing and attached to the switch actuating mechanism,

and extending outside the guide hole in all positions of the switch mechanism whereby friction of the pull element at the guide hole is minimized, a smooth, quiet actuation of the switch mechanism is assured, and the 20 pull end of the chain is insulated from the switch mechanism, substantially as described.

In testimony whereof I have signed my name to this specification, in the presence of two subscribing witnesses.

JAMES G. GIRLING.
